UNITED STATES PATENT OFFICE.

EDGAR A. BRIGGS, OF HOPKINTON, MASSACHUSETTS.

BRUSH.

1,115,165.

Specification of Letters Patent. Patented Oct. 27, 1914.

Application filed February 13, 1914. Serial No. 818,597.

To all whom it may concern:

Be it known that I, EDGAR A. BRIGGS, a citizen of the United States, and resident of Hopkinton, county of Middlesex, State of Massachusetts, have invented an Improvement in Brushes, of which the following description, in connection with the accompanying drawing, is a specification, like characters on the drawing representing like parts.

10 This invention relates to the construction of brushes.

The invention in its preferred form is particularly useful in connection with tooth brushes or brushes which it is particularly 15 desirable shall be kept in a sanitary condition or which shall be capable of ready sterilization. But the invention is equally applicable to brushes of varying sizes and for various purposes.

20 The object of the invention is to provide a brush in which the brush back shall be smooth and even, in which bristles shall be firmly locked in place so as to render removal impossible without destruction of the brush, 25 in which the brush shall be thoroughly sanitary, and in which the brush may be sterilized in boiling water or other liquids without injury to its construction.

The nature of the invention will appear 30 more fully from the accompanying description and drawings and will be particularly pointed out in the appended claims.

The drawings represent a preferred form 35 of brush and illustrate steps in the process of manufacture, involving the invention, the brush illustrated being a tooth brush.

In the drawings, Figure 1 is a view in perspective of a novel form of double ended tooth brush embodying the invention; Fig. 40 2 is a cross-section taken through a line of apertures in the brush back, and showing the steps in the process of inserting the bristles; Fig. 3 is a similar view after the bristles are inserted showing the steps in the process 45 of locking the bristles in place and finishing the brush.

The invention as already pointed out is applicable to brushes of various sizes and shapes made of various materials and used 50 for various purposes. It is particularly useful in connection with tooth brushes which obviously should be thoroughly sanitary and which with this invention may be sterilized at any time.

55 With this invention the back and handle of the brush may be made throughout of

metal so that the only non-metallic material in the brush are the bristles themselves. The construction is such that when the brush is completed it is impossible to pull out or remove the bristles or for them to work loose without the destruction of the brush back. There are no projecting parts or no parts liable to work loose and project from the back, thus insuring a perfectly smooth 60 back to the brush. 65

The brush shown in the drawings as illustrative of the invention is preferably made of aluminum, but any other suitable metal or material may be employed for that purpose. 70 The brush is shown as double ended having a handle 1 terminating in the brush backs 2 and 3, the former being shown as rectangular and elongated, and the latter as circular. These brush backs are connected to the body 75 of the handle 1 by peculiarly shaped necks 4 and 5 which enable one or the other of the brushes to be fitted into the mouth and brought into contact with any portion of the teeth needing cleansing. 80

So far as the invention herein involved is particularly concerned the shape of the back of the brush is not material and is equally applicable to any shape such as that illustrated at 2 or that illustrated at 3 or other 85 usual shapes.

The brush forming the invention results from the process which will now be described.

The back 2 is first provided of suitable material such as aluminum of proper shape, size and thickness, according to the required purpose. Pairs of apertures are then formed through the back as by drilling or punching, three of such pairs of apertures being 90 illustrated in Fig. 2, the members of each pair being designated at 6 and 7 respectively. These apertures should be of sufficient diameter to receive and hold snugly tufts of bristles of the desired size. A groove is 100 formed in the upper face of the back connecting the members of each pair of apertures, this groove may be formed coincidentally with the forming of the apertures, before, or after their formation and by any 105 suitable mechanical operation. A set of bristles is then provided for each pair of apertures, the set of bristles being when assembled of such diameter as when doubled to fill and snugly fit the apertures. These 110 bristles may be of any suitable material such as is employed in the manufacture of

brushes. Each set of bristles is then doubled in its middle, a wire 8 or other suitable device is inserted through the loop end of a set of doubled bristles, the wire followed by 5 the set of bristles is pulled up through one aperture as 6 of a pair of apertures, until the bristles project from the face of the back to the required extent. At the completion 10 of this step of the operation the set of bristles are in the position illustrated in the middle pair of apertures of Fig. 2. The loop end of the set of bristles is then bent over toward the back, the wire 8 is inserted through the aperture 7, and is pulled 15 through, pulling after it the loop end of the bristles until the bristles take the position illustrated in the left hand pair of apertures, in Fig. 2, with the central portion 20 of the bristles lying in the groove, and the bristles thus projecting in two tufts through the apertures from the bottom face 25 of the back. The loop end of each set is trimmed off then or subsequently leaving the bristles in the form shown in the right hand pair of apertures in Fig. 2.

A filler or locking plug is provided, and this is preferably of U or staple shape, and when the back of the brush is of metal preferably of the same metal. Such a filler is 30 shown at 9 in Fig. 3, and would, in the case of the brush particularly illustrated, be of aluminum. This filler is of the general shape of that portion of the apertures, and connecting groove lying above the bent middle 35 section of the bristles, but is somewhat larger in size, so that when it is forced into place it will completely fill the space above the bristles, wedge the bristles in, and lock them in place, and still project somewhat 40 above the surface of the back. This filler, such as 9, is next inserted in place and forced into place by driving or swedging until it fills up completely the space between the bristles and the back of the brush, and 45 locks the bristles firmly in place. The completion of this step of the operation is shown in the middle section of Fig. 3. When all the fillers have been inserted the back of the brush is then finished off by grinding

and polishing, or in any other suitable manner, thus removing the projecting portion of the fillers 9 and leaving the upper surface of the back smooth and even.

It will thus be seen that all the objects of the invention are accomplished, that the back of the brush is perfectly smooth, that there is nothing projecting therefrom excepting the bristles, that there is nothing which can work loose from the back, that the bristles are firmly locked in place, and cannot be removed or pulled out or work loose, that the brush is thoroughly sanitary, and especially when made of metal, comprises nothing but the metal of the back and the bristles themselves, and that it is capable 65 of sterilization in boiling water or other liquid.

Having thus fully described my invention, what I claim as new and desire to secure by Letters Patent is:

1. A brush comprising a back provided with apertures extending therethrough in pairs connected by a groove on the upper face of the back, a set of bristles in each pair of apertures having the middle portion 75 in said groove and the ends projecting through said apertures from the lower face of the back, a locking plug wedged into and filling said groove and apertures above the bristles and finished off flush with the upper 80 surface of the back.

2. A brush comprising a solid metal back provided with apertures extending therethrough in pairs connected by a groove on the upper face of the back, a set of bristles 85 in each pair of apertures having the middle portion in said groove and the ends projecting through said apertures from the lower face of the back, a staple shaped metal locking plug wedged into and filling said groove 90 and apertures above the bristles and finished off flush with the upper surface of the back.

In testimony whereof, I have signed my name to this specification.

EDGAR A. BRIGGS.
